UNITED STATES PATENT OFFICE.

ALEXANDER DOM, OF MOUNT HEALTHY, ASSIGNOR TO THE GLOBE COMPANY, OF CINCINNATI, OHIO.

PAPER-FILE.

SPECIFICATION forming part of Letters Patent No. 450,097, dated April 7, 1891.

Application filed October 10, 1890. Serial No. 367,690. (No model.)

To all whom it may concern:

Be it known that I, ALEXANDER DOM, a citizen of the United States, residing at Mount Healthy, Hamilton county, State of Ohio, have 5 invented certain new and useful Improvements in Paper-Files, of which the following is a specification, reference being had to the accompanying drawings, forming a part thereof.

10 The object of my invention is to provide a device for transferring letters, bills, or other office papers from a temporary file to a permanent box-file in order that the latter may be filed away in convenient order for reference, as will more fully hereinafter appear.

In the accompanying drawings, Figure 1 is a perspective view of a number of papers filed on a temporary double-arched file with the device for transferring said papers to a 20 permanent file, said transferring-wire being shown in position over the hollow vertical wires of the temporary file ready to be inserted therein in order to file the papers on said transferring-wire to be removed to the 25 permanent file. Fig. 2 is a perspective view of the permanent file-box with the papers filed therein, also showing the transfer-wire locked to position at one end of said file-box. Fig. 3 is a vertical section taken through one end 30 of the permanent file-box, transfer-wire, and its catch, showing the preferred mode of connecting said parts.

My invention consists of a transfer-wire A, bent substantially as shown, and a suitable 35 catch, as B, connected to the side or end of the permanent file-box C for the purpose of retaining said transfer-wire in position therein after the papers to be filed have been secured on said wire. The vertical extensions 40 a of the transfer-wire are adapted to enter within the hollow filing-tubes b of an ordinary double-arched file, as shown in Fig. 1, after which the operator grasps the papers, places his thumb or finger on the transfer- 45 wire, and gently lifts said papers and wire from contact with said temporary file and then places said papers and wire in the permanent file-box C, as shown in Fig. 2, the horizontal portion of said wire being sprung 50 beneath the catch B, in which position the papers are securely retained therein.

The vertical extensions a of the transfer-wire are adapted to enter and rest within suitable openings or recesses in the cross-strip a' of the permanent file-box or in suitable openings in the bottom of said box, said openings in connection with the catch B tending to retain said transfer-wire and the papers filed thereon in a permanent position within the box. 55

The permanent file-box may be of any desired configuration or construction, but is preferably formed as shown with the hinged top lid D and hinged side lid D', said lids having a suitable catch, as d, for connecting 60 them together. Each box may be suitably labeled and filed away for reference. If occasion should require an examination of any paper thus filed, the same is of ready access and may be examined without removal from 65 the permanent file-box. 70

The advantages of my invention are apparent. The means employed for transferring the papers from a temporary file to a permanent one and securing said papers therein is 75 simple of construction, ready and reliable in operation, and cheap of manufacture. Each file-box C is provided with a transfer-wire A and catch B, as aforescribed.

What I claim as new and of my invention, 80 and desire to secure by Letters Patent, is—

1. The permanent file-box C, having a catch B connected thereto, in combination with transfer-wire A, bent substantially as set forth, the vertical extensions of said transfer-wire 85 resting on the bottom of said box, the horizontal portion of said wire being sprung beneath said catch, substantially as set forth.

2. The permanent file-box C, having hinged lids D D', cross-piece a', and catch B, connected to one end thereof, in combination with transfer-wire A, the extensions a of said wire resting in openings formed in said cross-piece, the horizontal portion of said wire being sprung beneath said catch, all arranged sub- 90 substantially as set forth. 95

ALEXANDER DOM.
